(57) **CLAIM**

The ornamental design for an adjustable fixing apparatus for a cable, as shown and described.

DESCRIPTION

FIG. 1 is a front perspective view of an adjustable fixing apparatus for a cable of the claimed design.

FIG. 2 is a rear perspective view of the adjustable fixing apparatus for a cable of FIG. 1.

FIG. 3 is a front elevational view of the adjustable fixing apparatus for a cable of FIG. 1.

FIG. 4 is a rear elevational view of the adjustable fixing apparatus for a cable of FIG. 1.

FIG. 5 is a top plan view of the adjustable fixing apparatus for a cable of FIG. 1, and the bottom plan view is a mirror image thereof.

FIG. 6 is a right side elevational view of the adjustable fixing apparatus for a cable of FIG. 1, and the left side elevational view is a mirror image thereof; and,

FIG. 7 is a front elevational view thereof on a reduced scale shown in position of use.

The broken lines are for illustrative purposes only and form no part of the claimed design.
